RECEPTACLE

Edward Brosler, Pittsburgh, Pa.

Application December 31, 1929, Serial No. 417,754

11 Claims. (Cl. 220—17)

The present invention relates to a receptacle more particularly to that type commonly used as a refuse receptacle wherein a container for receiving material is removably positioned within a holder.

The adaptations or embodiments of this type of receptacle now commonly used comprise substantially an outer metallic holder and an inner metallic container adapted to be loosely positioned within the holder. A bail is hingedly secured to the inner container near its upper edge at diametrically opposite points and when not in use, is adapted to fall within the inner confines of the outer holder or container. A cover, hinged to the outer container is adapted to be operated by various foot or hand controlled mechanisms well known in the art.

The above type of receptacle, while intended to obviate all the inconveniences, unsanitary, and unsightly conditions arising out of the use of the old fashioned single receptacle, nevertheless fails, in material aspects, to accomplish the objects and results, necessitated by a desire for convenience and sanitary conditions.

Under normal conditions, due to the fact that the bail is secured to the outer surface of the inner container, a comparatively wide open space must exist between the inner and outer containers resulting in waste material or refuse finding its way between the containers, subsequently to decay and create an unsanitary condition. The bail, located as it is, renders it difficult to be grasped and in addition is in a position where it easily and readily becomes soiled and greasy from the refuse thrown into the receptacle.

My invention has for its purpose to improve upon the above type of receptacle whereby to correct the disadvantages noted.

Another object of my invention is to provide a receptacle of the type described wherein the lifting means for the inner container is protected and maintained in a clean and sanitary condition.

Another object of my invention is to provide a container and a holder therefor wherein the possibilities of material finding its way between the container and holder are eliminated.

Another object of my invention is to provide a container and a holder therefor and means for locking one to the other.

Another object of my invention is to provide a container of the type described with means for selectively lifting either the inner container or holder.

Additional objects of my invention will disclose themselves in the following description of my invention in conjunction with the drawing wherein

Fig. 1 is a side view of the outer container or holder comprising an element of my invention.

Fig. 2 represents a side view in perspective of the inner container.

Fig. 3 is a side view in perspective of the structure shown in Figs. 1 and 2 in assembled relationship.

Fig. 4 illustrates the outer container in perspective of another specie of my invention.

Fig. 5 represents the inner container in front view perspective.

Fig. 6 illustrates the structures of Figs. 4 and 5 in assembled relationship.

Referring to Fig. 3, an outer container or holder 6 is shown adapted to receive an inner container 1 illustrated in Fig. 2 and shown in assembled relationship in Fig. 3. The container 75 1 is provided with an upper circumferential flange adapted to either frictionally engage the inner wall of the outer container or may be of such size as to overlie the upper edge of the holder 6, thereby closing, in either case, the space 80 normally existing between the two containers and so eliminating all possibility of waste material finding its way therein.

Secured in a customary manner to the inner receptacle near its upper edge is a bail 4 provided with integral hook extensions 14 at both extremities for a purpose hereinafter set forth. The ferrules 5, providing the pivoting means for the bail member, are of such dimensions as to slide within the notches 7 and 8, thereby allowing 90 free pivotal movement of the lifting means 4 and 14.

In forming notches 7 and 8, the metal, instead of being removed, is bent outwardly as shown to provide lugs 12 and 13. As clearly shown in 95 Fig. 3, these lugs are so proportioned that in raising the bail 4 to a vertical or lifting position, the hooks 14 will grasp them thereby permitting the holder and inner container to be lifted and transported as a unit. With the flange 2 resting on the upper edge of the holder, a clamping action will be exerted by the hooks engaging the lugs thereby forcing the inner container and holder into locking engagement.

In order to utilize the bail 4 for removing the inner container from its holder, a lifting force is exerted before the bail reaches a vertical position. This force will raise the inner container a distance sufficiently to prevent any likelihood of the hooked portion of the bail interengaging with the lugs 12 and 13 after which the lifting means may be raised to a vertical position and the lifting operation completed.

As stated, above, my invention is adapted to be used with any of the manually or foot operated mechanisms for raising the cover. One particular type not shown serves to lift the cover by raising the inner container slightly. This can be accomplished by means of a foot lever hinged or pivoted adjacent the lower edge of the outer 115 120

container or holder and operating through the bottom of said holder against the bottom of the inner container. This type of cover lifting mechanism when used in combination with my device 5 produces an improved result in that by raising the inner container, it removes the hooks 14 out of swinging engagement with the lugs 12 and 13, thereby eliminating the necessity for exerting an upward lifting force on the bail prior to its 10 reaching a vertical position.

In the species disclosed in Figures 4 to 6, notches 16 and 17 are formed in the upper edge of the holder 6, the bail 4 on the inner container being shaped as shown in Fig. 6 with an offset 15 portion 18. Upon assembling the inner container and its holder, the bail 4 is adapted to fall into the notches 16 and 17 as clearly disclosed in Fig. 6, the offset portion 18 resting beyond the confines of the assemblage and in a position where it will 20 remain clean and be easily accessible at all times.

If desired, the notches may be formed at diametrically opposite points as shown in Fig. 3 and the container may then be supported or not in said notches. In either event, the ferrules 19 25 and 20 instead of the bail should preferably rest in the notches. This construction would enable the entire bail to lie at all times outside of the assemblage as illustrated in Fig. 3. In addition, a larger inner container providing a substantially 30 snug fit with the holder could be used, thereby practically eliminating the space normally existing between the container and holder and increasing the capacity of the receptacle to a maximum.

35 The above disclosures constitute merely embodiments of my invention and I do not wish to be confined to the exact details and structures described except insofar as they are limited by the claims.

40 I claim:

1. In combination, a container for receiving material, a holder for said container and carrying means swingably attached to said container and constructed to interconnect with said holder, 45 when said carrying means is swung to carrying position.

2. In combination, a container having a bail and a flanged opening, a holder for loosely receiving said container, said holder having an upper rim, and means associated with said bail 50 adapted to clamp said flange to the upper rim of said holder to close the opening to the space between said container and holder, said means also providing means for removing said container from said holder.

3. In combination, a pair of nesting receptacles, carrying means swingably attached to one of said receptacles, said carrying means being provided with means to interconnect with the 60 other of said receptacles by movement of said bail to its carrying position whereby both of said receptacles may be lifted as a unit by said carrying means.

4. In combination, an outer container, an inner 65 container nesting within said outer container and having a pivoted carrying means comprising a bail mounted in proximity to the upper edge thereof, said outer container extending at least to the approximate plane of the upper edge 70 of said inner container and being notched at its upper edge to receive said bail and permit said bail to extend beyond the outer confines of said outer container.

5. In combination, an outer container, the up- 75

per edge thereof being notched, an inner container nesting within said outer container, said outer container extending at least to the approximate plane of the upper edge of said inner container, said inner container being provided with a bail swingably mounted in proximity to the upper edge thereof, and so constructed as to extend, when in a horizontal position, beyond the 80 confines of said outer container, said notches being located to receive said bail, with said inner container nesting within said outer container. 85

6. In combination, a pair of nesting containers, the inner container being provided with pivoted carrying means comprising a bail whereby said container may be lifted, a portion of the upper edge of the outer container being removed to accommodate said bail while said inner container is nesting within said outer container to permit said bail to extend beyond the outer confines of said outer container, and a cover for said outer 95 container. 90

7. In combination, an outer container, an inner container nesting within said outer container, a cover for said outer container, said cover being in effect supported in its closed position on the upper edge of said outer container, said outer container and cover assemblage being provided with diametrically positioned openings at the junction of said outer container and cover, and a bail for said inner container, said bail being attached to said inner container, in proximity to its upper edge and extending through said opening to beyond the confines of said outer container. 100 105

8. An inner container and an outer container, said outer container extending at least to the approximate plane of the upper edge of said inner container, a carrying bail swingably mounted on and secured to said inner container, said bail being of such dimensions as to extend beyond the 110 confines of said outer container, said outer container having a portion removed therefrom to receive said bail. 115

9. A pair of nesting receptacles, the outer receptacle extending at least to the approximate plane of the upper edge of said inner receptacle 120 and being notched at its upper edge, a bail swingably secured to the inner of said nesting receptacles and extending through the notched portion of said outer receptacle and means mounted on one of said receptacles and movable with respect 125 thereto for locking said bail to said outer receptacle.

10. An inner container and an outer container, said outer container extending at least to the approximate plane of the upper edge of said inner container and being notched at its upper edge, a bail having a radial dimension greater than that of said outer container, means for pivotally securing said bail to said inner container, said pivotally securing means passing through 130 the notched portion of the upper edge of said outer container. 135

11. An inner container and an outer container, said outer container extending at least to the approximate plane of the upper edge of said inner container, a bail having a radial dimension greater than that of said outer container, means for pivotally securing said bail to said inner container, the upper edge of said outer container being notched to permit said bail to lie outside the 140 145 confines of said outer container and below the upper edge thereof.

EDWARD BROSLER.
